TIE AND SPACER FOR CONCRETE FORMS

Filed March 23, 1927

UNITED STATES PATENT OFFICE

ARTHUR M. KINNINGER, OF DAYTON, OHIO, ASSIGNOR OF ONE-HALF TO CARL A. KINNINGER, OF DAYTON, OHIO

TIE AND SPACER FOR CONCRETE FORMS

Application filed March 23, 1927. Serial No. 177,701.

My invention relates to forms for concrete structures and more particularly to a form or wall tie for transversely connecting the walls of a concrete form in predetermined spaced relation.

It is customary in the construction of concrete forms to provide side walls of boards attached to uprights or studding. The uprights or studdings of opposite walls are oppositely disposed and are interconnected by transverse wires which pass between the boards and around the studdings or uprights at opposite sides of the forms, the ends of which wires are then twisted together. In such case the transverse ties do not per se determine the width of the walls or spacing of the form walls. It is usual in such construction to employ wooden spacers which are interposed at intervals between the form walls and which must be removed as the concrete is formed.

The present form of tie is pre-formed in predetermined sizes in accordance with the thickness of the concrete wall or the spacing of the form walls. The tie is adapted to determine the spacing of the walls of the forms and to prevent spreading. The use of the present tie also enables the elimination of a portion of the upright struts or studding or the spacing of such struts at greater intervals.

In its preferred form the present tie comprises a single strand of wire having at one end a short cross arm attached thereto and at its opposite end in predetermined spaced relation with the first cross arm, a pair of such short cross arms spaced one from the other a distance substantially equal to the thickness of the boards forming the side wall of the form. In applying the ties the end having the single cross arm is passed between successive form boards adjacent to an upright strut or studding with the short cross arm at the inner side of the form wall. The wire strand extending outwardly from the form wall is passed around the strut or studding and thence again between the form boards and across the form and intermediate successive form boards of the opposite form wall with the closely spaced cross arms lo-

cated inside and outside the form boards of the second wall. The tie is thus engaged about a strut or studding at one side of the form but not so engaged at the opposite side. Consequently the struts or studding may be offset in relation with each other. The successive ties are arranged in reverse relation, that is to say, whereas the end of the tie having the single cross arm is passed about the strut or studding at one side of the form and the double cross arms in the opposite end of the tie straddle the form board of the opposite wall in the next succeeding tie, longitudinally of the form, will be arranged with its single cross arm engaging the last mentioned wall of the form and extended about a strut on the side of the form with which the double cross arm was engaged and the end of the second tie, carrying the spaced double cross arms will be engaged with the opposite form wall corresponding to that contiguous to the strut or studding with which the single cross arm end of the preceding tie was engaged.

Obviously the wall engaging cross arms may be connected with the tie in various ways, and in lieu of separate cross arms these may be formed as sheet metal stampings to which the tie is connected. In lieu of the cross arms the tie may be provided with knots or spurs by which it is engaged with the form walls.

The object of the invention is to simplify the structure as well as the means and mode of bracing and tying form walls for concrete structures whereby they will not only be cheapened in construction, but will be more uniform and accurate in the spacing of the walls, of increased strength and durability, and unlikely to get out of shape or alignment.

A further object of the invention is to provide an improved form of tie which may be easily and quickly applied and which will predetermine the spacing of the form walls.

A further object of the invention is to provide a form tie which will tend to hold the form boards in their adjusted position thus minimizing the use of nails and will further reduce to a minimum the use of struts or studding.

With the above primary and other incidental objects in view as will more fully appear in the specification, the invention consists of the features of construction, the parts and combinations thereof and the mode of operation, or their equivalents, as hereinafter described and set forth in the claims.

Referring to the accompanying drawing wherein is shown the preferred, but obviously not necessarily, the only form of embodiment of the invention, Fig. 1 is a perspective view of a portion of a concrete form to which the present form tie has been applied. Fig. 2 is a top plan view of a portion of a concrete form illustrating the application of the present tie in successive reversed positions. Fig. 3 is a perspective view of a tie removed from the form. Figs. 4 to 10 inclusive illustrate various modifications and variations of the form tie forming subject matter hereof.

Like parts are indicated by similar characters of reference throughout the several views.

In the accompanying drawings 1—1 are form boards superposed in vertical planes one upon another to form the side walls of a concrete form. These boards 1—1 comprising the form walls are supported at intervals by vertical struts or studding 2—2 located on the outer side of such form walls. In the usual method of constructing form walls the struts 2—2 are located opposite each other in pairs. However, in the present construction, the preferred arrangement is to offset the struts or studding 2 in diagonal spaced relation so that the struts or studding on one side of the form are opposite points substantially half way between successive struts or studding pertaining to the opposite form wall. Ordinarily the form boards 1—1 are nailed to the struts or studding. In the present instance it is not necessary to nail the boards at frequent intervals other than to attach the topmost boards when the wall structure has been completed. It may be desirable to place occasional nails in the side walls 1—1 and studding or struts, but for the most part the form tie forming the subject matter will not only determine the spacing of the walls but will also maintain the form boards in their vertically aligned relation and will secure the form boards to the support struts 2.

The present commercial form of tie as illustrated in Fig. 3 comprises a strand 3 of wire or other suitable connector having at one end thereof a short cross arm 4 and at its opposite end a pair of such short cross arms 5 and 6. The cross arms 4, 5 and 6 are short lengths of metal which are interposed in bights or reverse bends 7 and 8 respectively of the tie band 3. Such bights or reversed bends 7 and 8 with the interposed short cross arms 4, 5 and 6 are then electrically welded to secure such arms in place. These ties are

made in predetermined sizes wherein the width of the desired concrete wall together with the thickness of the form walls and the size of the struts or studding 2 are computed, and the strand 3 is made of such length that it will extend outwardly through one form wall thence about the supporting strut or studding and across the form and between the boards of the opposite form wall when the form walls are in their properly and predetermined spaced relation.

In assembling the forms and applying the tie the strand 3 is interposed between successive form boards 1—1 with the short cross arm 4 at the inner side of such boards and adjacent to one of the struts or studding 2. The strand 3 thus extending outwardly from the form wall is then passed around the strut or studding as shown at 9 and thence again between the same form boards 1—1 and is extended across the form to the opposite wall thereof. At the opposite side of the form the short cross arms 5 and 6 straddle the successive form boards 1—1. The cross arms 5 and 6 are spaced apart a distance substantially equal to the thickness of such form boards. Thus the arm 6 limits the outward movement of the form wall relative to the opposite wall while the inner cross arm 5 maintains the succeeding form boards in a common vertical plane. Inasmuch as the studding or uprights 2 are arranged in staggered relation the longitudinal succession of ties throughout the length of the form are arranged in alternating reversed relation. Also, if desired, the vertical succession of ties pertaining to each studding or strut 2 may be reversed as shown in Fig. 1. That is to say, the bights in the ends of the succeeding ties may be extended in opposite directions about the strut or upright so that the cross arms 4 are disposed first at one side and then the other of the strut or studding.

In lieu of welding the terminal bights enclosing the cross arms 4, 5 and 6 as has been described, these cross arms may be secured by twisting the enclosing bights of the tie member 3 as indicated at 7' in Fig. 4. Likewise, instead of cross arms 4, 5 and 6 of rectangular cross section, such arms may comprise short lengths of round rod stock as illustrated in Fig. 4.

As a further modification anchor members may be formed from sheet metal and interconnected by an intermediate tie strand as illustrated in Fig. 5. In this construction there is provided at one end of the strand 3 an anchor member comprising a horizontal flat sheet metal web portion 9 from one margin of which projects perpendicularly thereto two parallel spaced fingers 10, while from the opposite margin project downwardly two dependent like spaced fingers 11. The web portion 9 is to be interposed between succeeding form boards with the spaced fingers 10

10 and 11 straddling the boards above and below the web portion 9. At the opposite end of the strand 8 is provided an anchor member 12 having single upstanding and dependent fingers 13 and 14 which engage with the inner side of the form wall in the same manner as the cross arm 4 of the described construction. Instead of interconnecting such anchor members 9 and 12 by an intermediate strand 8, such anchor members may be formed integral with an intermediate flap strip of material 15 shown in Fig. 6. In such case the strip 15 is twisted at 16 to enable it to pass about the supporting struts or studding 2. The fingers 13 and 14 at one end of the strip engage the inner side of the form wall while the spaced fingers 10 and 11 at the opposite end of the strip 15 straddle succeeding boards of the opposite wall of the form.

In lieu of the spaced cross arms or fingers heretofore described, the tie or spacer strands may be provided with spaced knots 17 as illustrated in Fig. 7. In this instance the tie strand 3 is shown as provided with a single knot at one end, corresponding to the cross arm 4 and serving a like purpose, while at the opposite end of the strand is a pair of spaced knots in lieu of the cross arms 5 and 6.

While for economy of form construction the herein before described diagonal disposition of struts or studding is desirable, in which case the tie or spacer forming the subject matter hereof is engageable with one wall and about the studding or support and is engageable with the opposite wall independent of a studding or upright, there are conditions met in building construction wherein it may be desirable to employ oppositely disposed uprights or studdings. In such case, a tie strand 3 having a single cross arm 4 at each end as illustrated in Fig. 8 may be employed. In such case, a bight is formed at each end of the tie strand 3 to embrace the oppositely disposed studding or uprights. In other words, in lieu of the double anchor fingers 5 and 6, which are intended for engagement with the form boards intermediate succeeding studding or uprights, the single cross arm 4 with its studding engaging bight is duplicated at the opposite end of the tie.

For those conditions where it is desired to brace a form intermediate uprights or studding or at points where uprights or studding are not available, it is quite practical to duplicate the spaced anchor fingers or cross arms 5 and 6 at each end of the tie strand as shown in Fig. 9. By providing such cross arms or anchor fingers 5 and 6 in spaced pairs at each end of the strand 3, such strand may be utilized to brace and tie together the side walls of the concrete form wholly independent of supporting struts or studding. The connecting strands 3 and 15 being comparatively thin are easily embedded in the margins of

the form boards by the weight of the succeeding boards above or by a hammer blow. Thus the existence of intervening crevices or cracks sufficiently large to permit leakage of the concrete is entirely avoided. The use 70 of the present form of tie insures the proper and accurate spacing of the form walls and anchors them one to another to prevent bulging or collapse under the pressure of the concrete there within. Moreover, by use of the 75 present form of tie and spacer member the use of nails is almost entirely obviated. The top course of boards is preferably nailed to prevent the boards from floating up or rising as concrete is poured into the form. While, if desired, the boards may be nailed 80 to the studding or uprights in the usual manner, it has been found in practice that the present tie is sufficient under all ordinary circumstances and conditions to secure the 85 form boards in place. Not only does the use of these ties contribute to the strength of the form and facilitate the rapidity with which a form may be constructed, but they also very materially facilitate the removal 90 of the form after the concrete has set. This is done by cutting the bight of the wire strand passing about the studding or uprights on one side of the wall and by cutting or knocking off the anchor fingers 6 at the opposite 95 side of the wall leaving the intermediate tie strand 3 embedded in the body of concrete.

While the present tie is primarily intended for use in securing and bracing concrete forms it will also be found useful in securing 100 crating, bracing and reinforcing large shipping boxes, for racking materials or for bracing parts of buildings. Obviously, the tie member may be made in any length and of increased strength to accommodate it to 105 various conditions of use.

From the above description it will be apparent that there is thus provided a construction of the character described possessing the particular features of advantage before enumerated as desirable but which obviously is susceptible of modification, in its form, proportions, and arrangement of parts, without departing from the principle involved or sacrificing any of its advantages.

While in order to comply with the statute the invention is described in language more or less specific as to structural features, it is to be understood that the invention is not limited to the specific details shown, but that the means and construction herein disclosed comprise the preferred form of several modes of putting the invention into effect, and the invention is therefore claimed in any of its forms or modifications within the legitimate 115 and valid scope of the appended claims.

Having thus described my invention, I claim:

1. In a wall tie for concrete forms, and the like, a tension strand to be interposed between 120

successive boards of form walls and engageable about a supporting strut exteriorly in the form and anchor means carried at opposite ends of the strand engageable with the 5 opposite walls of a concrete form serving to secure the walls in predetermined relation with the supporting strut.

2. In a tie and spacer for concrete form walls, a tie strand, anchor means at one end thereof enabling the engagement of the one wall of the form with a wall studding and anchor means at the opposite end of the strand engageable with the form wall at the opposite side of the mold independent of a 10 wall studding.

3. In a tie and spacer for concrete forms, a tie strand, an anchor projection at one end of the strand engageable with the inner face of one form wall, the strand extending thence 20 outwardly and around a wall strut and then in reverse direction across the form, and a pair of spaced anchor projections at the opposite end of the strand engageable with the opposite form wall.

4. In a tie and spacer for concrete forms, a tie strand, an anchor hook at one end of the strand engageable with a wall strut of one wall of the form and spaced projections at the opposite end of the strand between which 30 a form board of the opposite wall is engageable.

5. In a tie for concrete forms, a tie strand to be interposed between successive boards of the form walls, one end of the strand being formed into a bight for engagement about a wall studding reinforcement, anchor means at the end of the bight engageable with the adjacent form wall thereby connecting the wall and studding and anchor means at the 40 other end of the strand engageable with the interior and exterior faces of the opposite wall.

6. Means for anchoring the walls of a concrete form, or the like, including a transverse tie strand interiorly of one wall of the form, the strand passing outwardly about a wall studding and thence transversely across the form and anchoring the opposite end of the strand both interiorly and exteriorly upon 50 the opposite form wall.

7. A tie for concrete forms comprising a tie strand to extend transversely of the form and about a reinforcement strut exteriorly thereof and be interposed between successive boards of the form walls, and means carried by the strand in predetermined spaced relation and engageable with the interior lateral faces of the form walls to prevent the withdrawal of the strand from between the boards. 55

8. A tie strand for concrete forms comprising a tie strand to be interposed between successive boards of the form walls and about a wall strut exteriorly thereof, spaced anchor means carried by said strand engageable with the adjacent form wall at one side of the strut

and additional anchor means carried by the strand portion at the other side of the strut for anchoring the opposite end of the strand to the opposite form wall.

9. A tie strand for concrete forms comprising a tie strand to be interposed between successive boards of the form walls, a bight formed in one end of the strand for engagement about a wall studding, an anchor means carried by the bight engageable with the form wall to prevent disengagement of said bight from the studding, and means for anchoring the opposite end of the strand to the opposite wall of the form. 70 75

10. A tie for concrete forms, and the like, comprising a tie strand to extend about a form wall strut and transversely of the form and cross arms carried thereby in predetermined spaced relation for anchorage engagement at opposite sides of the strut with the 80 opposite form walls.

11. A tie for concrete forms and the like, comprising a tie member to extend transversely of the form and about an exterior reinforcement member and a plurality of laterally projecting arms carried thereby for anchorage engagement with the opposite form walls, an arm at one end of said tie member being anchored interiorly of the form at one side of said reinforcement member, the 90 tie member extending thence exteriorly of the form about such reinforcement member and thence in reverse direction across the form, and an arm at the opposite end of the tie having engagement with the opposite wall of the 95 form. 100

12. The herein described method of constructing concrete forms including arranging form wall studding of opposite spaced walls in staggered spaced relation and transversely 105 tying a wall studding at one side of the form with the opposite form wall at a point intermediate succeeding studding.

13. The herein described method of constructing concrete forms including offsetting the supporting studding of parallel spaced form walls whereby the studding will not be opposite each other and transversely interconnecting oppositely disposed points of the respective form walls at points contiguous to a supporting studding of one wall with a point located in spaced relation with the studding of the opposite wall. 110 115

14. The herein described method of constructing concrete forms, including providing spaced form walls and arranging reinforcing studding for the respective form walls at spaced intervals in diagonally offset positions relative to the studding of the opposite form wall and interconnecting the 120 studding of each wall with the opposite form wall independent of the studding pertaining to such opposite wall. 125

15. In a construction of the character described, the combination with a concrete 130

- form including spaced side walls and exterior reinforcement members, of a tie member extending exteriorly about a reinforcement member with one end of the tie anchored to the adjacent side wall of the form and the other end of the tie extending at the opposite side of the reinforcement member transversely across the form and anchored to the opposite form wall. 5
16. In a construction of the character described, a tie strand having a bight formed therein, the arms of which are of unequal length, said bight being engageable about an exterior reinforcement member, of a concrete form and means carried by said arms for anchoring the shorter arm to the side wall of the form adjacent to said reinforcement member, and for anchoring the longer arm to the opposite side wall of the form. 10
17. A tie strand adapted to be passed exteriorly about an exterior reinforcement member of a concrete form and thence through the adjacent side wall of the form at opposite sides of the reinforcement member, an enlargement adjacent one end of said strand engageable with the interior face of the adjacent side wall at one side of the reinforcement member and an enlargement at the opposite end of the strand extending on the opposite side of the reinforcement member engageable with the exterior side of the opposite side wall of the form. 15
18. A tie strand to be interposed between wall boards of a concrete form and cross arms at its opposite ends, said strand being adapted to extend about and on opposite sides of an exterior reinforcement member of a form with the cross arm at one end positioned interiorly of the form wall at one side of the reinforcement and with the cross arm at the opposite end of the strand extending on the opposite side of the reinforcement member positioned exteriorly of the opposite side wall of the form. 20
19. A tie strand, anchor means for engaging the strand interiorly of the side wall of a concrete form, said strand being extendable outwardly through said wall, thence about an exterior reinforcement member for said wall, and in reverse direction on the opposite side of the reinforcement member across the form and anchor means for engaging such reverse portion with the exterior side of the opposite wall of the form. 25
20. In a construction of the character described, a tie strand having a bight therein, and anchor means at the end of the bight engageable interiorly of the side wall of a concrete form with the bight enclosing an exterior reinforcement member for said wall to secure said form wall to the reinforcement member. 30
21. In a construction of the character described, a tie strand having a bight formed therein, anchor means at the extremity of the tie strand engageable with the side wall of a concrete form from which the strand extends transversely of the form, the bight being engageable about a reinforcement member exteriorly of the opposite side of the form. 35
22. In a construction of the character described, a tie member extendable about and on opposite sides of an exterior reinforcement member for a concrete form and anchor means at the opposite ends thereof engageable with the opposite side walls of the form. 40
23. A molding form for concrete construction work comprising in combination, spaced rows of upright posts having the posts of one row arranged in staggered relation relative to the posts in the other row; a plurality of boards stacked edgewise against each row of posts, providing spaced retaining walls; and flat, comparatively thin, metal struts anchored to the respective posts, all of the struts on each post in each row having provisions to support alternate boards of both retaining walls in properly spaced and stacked relation and against their respective row of posts. 45
24. In a construction of the character described spaced form walls each comprising a succession of wall boards in marginal abutting relation and exteriorly disposed vertical supporting struts, two reversely disposed substantially T shaped anchor members, the transverse head portions being engageable in overlapping relation with the adjacent portions of abutting boards, the stems of which are extendable between the boards into engagement with supporting struts on the sides of said boards opposite the sides engaged by said heads, said anchor members being interconnected with each other into pairs. 50
25. In a construction of the character described spaced form walls each comprising a succession of wall boards in marginally abutting relation and exteriorly disposed vertical supporting struts and tie members connecting said form walls at spaced intervals each tie member including two reversely disposed substantially T shaped anchor members, the transverse head portions being engageable in overlapping relation with the adjacent portions of abutting boards, the stems of which are extendable between the boards into engagement with supporting struts on the sides of said boards opposite the sides engaged by said heads, said anchor members being flexibly interconnected with each other. 55
26. Means for securing successions of horizontal wall boards in two spaced vertical series to exteriorly disposed vertical struts, including a pair of headed members interposed between succeeding boards of the opposite series with their heads overlapping the inner faces of succeeding boards and stem 60

portions connected with the heads extending outwardly between the boards and transverse tie means also extending between succeeding boards and interconnecting the outward extending stem portions of the respective headed members.

27. Means for securing successions of horizontal wall boards in two spaced vertical series to exteriorly disposed vertical struts including a pair of interconnected headed members interposed between the succeeding boards of the opposite series with their heads overlapping the inner faces of succeeding boards and stem portions extending from such heads outwardly between succeeding boards into engagement with the exteriorly disposed struts, and a transverse tie portion interconnecting such headed members one with the other about the exteriorly disposed struts.

28. Means for securing successions of horizontal wall boards in two spaced vertical series to exteriorly disposed vertical struts, including a pair of headed members interposed between the succeeding boards of the opposite series, with their heads overlapping the inner faces of succeeding boards, and stem portions connected with the heads and extending outwardly between the boards, into engagement with the exteriorly disposed struts, said outwardly extending stem portions being flexibly interconnected with each other.

In testimony whereof, I have hereunto set my hand this 22nd day of March, A. D. 1927.

ARTHUR M. KINNINGER.
